(57) **CLAIM**

The ornamental design for a charging device, as shown and described.

DESCRIPTION

FIG. 1 is a top perspective view of a charging device showing our new design;

FIG. 2 is a bottom perspective view thereof;

FIG. 3 is top view thereof;

FIG. 4 is a bottom view thereof;

FIG. 5 is a back view thereof;

FIG. 6 is a front view thereof;

FIG. 7 is a side view thereof;

FIG. 8 is a bottom perspective view of a second embodiment of the charging device;

FIG. 9 is a front view thereof;

FIG. 10 is a bottom view thereof; and,

FIG. 11 is a back view thereof.

The broken lines in the figures represent portions of the article which form no part of the claim.
